United States Patent Office

Des. 177,327
Patented Apr. 3, 1956

177,327

AIRPLANE

Kenneth F. Holtby and Verne L. Hudson, Wichita, Kans.,
assignors to Boeing Airplane Company, Wichita, Kans.,
a corporation of Delaware

Application February 28, 1955, Serial No. 34,762

Term of patent 14 years

(Cl. D71—1)

FIG. 1

FIG. 2

FIG. 3

Des. 177,327

PAGE 2

FIG. 4

FIG. 5

FIG. 6

FIG. 7

Fig. 1 is a side elevation of an airplane embodying our new design;

Figs. 2 and 3 are front and rear elevations thereof, respectively, the landing gear being shown in broken lines;

Fig. 4 is a front perspective view looking upward from a point at the side of the plane;

Fig. 5 is a rear perspective view looking upward from a point beneath the plane;

Fig. 6 is a top plan view thereof; and

Fig. 7 is a side perspective view thereof.

The essential features of our design reside in the portions shown in full lines.

We claim:

The ornamental design for an airplane, as shown and described.
